UNITED STATES PATENT OFFICE.

AUGUST DABRASKY, OF WASHINGTON, DISTRICT OF COLUMBIA, AND GEORGE W. BEATTY, OF DECATUR, ILLINOIS.

MOUNT FOR GUNS.

Application filed November 12, 1926. Serial No. 148,003.

(GRANTED UNDER THE ACT OF MARCH 3, 1883, AS AMENDED APRIL 30, 1928; 270 O. G. 757.)

The invention described herein may be manufactured and used by or for the Government for governmental purposes without the payment to us of any royalty thereon.

5 This invention relates to mounts for guns.

In the present state of development of anti-aircraft gunnery automatic guns are employed at all ranges under three thousand yards because of the difficulty in maneuvering artillery to provide for the rapid changes which such low positions usually involve and also on account of the wide variations in the functioning of fuses at these short intervals.

15 The mission thus assigned to the automatic guns of the .50 caliber and the 37 m/m type requires that a mount be provided which is capable of rapid elevation, which is arranged for convenience of operation 20 and which possesses stability in all firing positions.

Certain mounts which have been arranged for convenience in operation by employing an elevating device consisting of a system 25 of levers lack rapidity of elevation and also stability. These mounts raise the gun bodily while rotating it about its axis so that the actuating movement required to elevate the gun a given amount is greater than 30 would be required if the gun turned on a fixed axis. Such bodily elevation of the gun coupled with an abnormal reduction in the base of the support entails so great a sacrifice in stability that the mount does not 35 function properly at elevations above 45°.

In the present invention the elevating mechanism likewise consists of a system of levers to obtain a shifting axis of rotation but the arrangement has been altered to 40 maintain a substantially fixed base at all elevations, to reduce the actuating movement below that required on a fixed axis of rotation, to provide the lowest possible mounting for all angular positions of the gun, to fix the point of application of the thrust to the mount and to associate an equilibrator with one of the levers of the system.

45 With the foregoing and other objects in view, our invention resides in the novel arrangement and combination of parts and in the details of construction hereinafter described and claimed, it being understood

that changes in the precise embodiment of the invention herein disclosed may be made 55 within the scope of what is claimed without departing from the spirit of the invention.

A practical embodiment of the invention is illustrated in the accompanying drawings, 60 wherein:

Fig. 1 is a view in the side elevation and partly in section of a mount constructed in accordance with the invention and showing the position of the parts at zero elevation.

Fig. 2 is a similar view showing the position of the parts at an elevation of 80°.

Fig. 3 is a diagrammatic view indicating the position of the parts at varying elevations.

Fig. 4 is a plan view; 70

Fig. 5 is a sectional view on the line 5—5 of Fig. 2;

Fig. 6 is a sectional view on the line 6—6 of Fig. 5;

Fig. 7 is a sectional view on the line 7—7 75 of Fig. 6;

Fig. 8 is a side view of the rear depending lever;

Fig. 9 is a plan view of the bell crank lever; 80

Fig. 10 is a side view of the bell crank lever;

Fig. 11 is a rear elevation of the top carriage;

Fig. 12 is a plan view of the bottom carriage; 85

Fig. 13 is a fragmentary sectional view showing manner of securing the depending lever;

Fig. 14 is a plan view of the front lever; 90

Fig. 15 is a side view of the front lever;

Fig. 16 is a sectional view on the line 16—16 of Fig. 14.

Referring to the drawings by numerals of reference: 95

The mount comprises a bottom carriage 11 which is shown as being secured to the frame 12 of a wheeled vehicle but which may equally well be attached to a fixed base or supported by a tripod. The carriage is 100 formed with a central pivot 13 and an annular trackway 14 for rotatably mounting a support or top carriage 15 which carries training gear 16 engageable with a fixed gear ring 17 on the bottom carriage. 105

The top carriage is formed with a pair of

spaced up-rights 18 and a horizontally extended arm 19 and these elements mount an elevating mechanism constituted by a system of levers which according to their position and the characteristics of the gun to be mounted may consist of single members or pairs of members. The gun is connected to this system of levers at two points both of which are preferably in rear of the center 10 of gravity of the tipping parts indicated at 20.

The rear connection of the gun to the carriage is had by means of a depending lever 21 pivoted to the up-right 18 and to the bottom portion of the gun at a point 22 which is located in such a manner that the movement of the lever on initial elevation of the gun from the horizontal position is on a descending arc. Because of interference with 15 the feed mechanism of the particular gun shown, only one lever is employed.

The front connection of the gun to the carriage is effected by means of the lever 23 pivoted to the gun on the center line of 25 bore and to a nut 24 which is movable along a screw 25 mounted on the extremity of the arm 19 and characterized principally by its position of inclination in the general direction of the elevating movement.

30 The third member completing the system consists of a bell crank lever 26 pivoted to the front lever 23 at a point 27 intermediate its ends and forwardly of the center of gravity 20 of the tipping parts and pivoted to the upright 18 at a point 28. Inasmuch as the lever 26 serves to transmit the thrust of the gun to the mount, its angular position with respect to the horizontal plane of the top carriage is to be kept at a minimum. 35 Further considerations of compactness, low mounting, the inclination of the screw 25 and the proper functioning of the levers determine the position of the point 28 which according to the present arrangement when 40 the gun is at zero elevation is included in a perpendicular plane passing through the pivotal attachment of the rear lever 21 to the up-right.

The short arm of the bell crank lever is 45 utilized for connection with a horizontally disposed equilibrating device herein shown as consisting of a spring actuated piston 29 working in a cylinder 30 secured to the top carriage.

50 The actuating mechanism 31 for rotating the screw 25 and causing the nut 24 to travel up the guide-ways 32 is positioned for the convenience of the operator who is to sight through a telescope (not shown) fixed to the gun in the vicinity of the axis of its rotation.

55 It will be noted from an inspection of Fig. 3 which shows the positions numbered 1 to 10 of the links as resultants of the advance of the nut on the elevating screw in increments of 2 inches, that their regular curve

60 defined by the pivotal attachment of the front lever and the gun during movement from 0° to 80° elevation results in abnormal angular displacement of the rear lever and consequent elevation of the rear end of the gun indicated on the general line cd. This arrangement provides a low mounting with sufficient clearance at all elevations.

65 It will also be apparent that the reaction of the rear lever in drawing the breech end of the gun forward combined with the gain in elevation by reason of employing an inclined screw considerably reduces the actuating movement necessary to elevate the gun and thereby permits rapid maneuvering of 70 the piece.

75 The particular gun for which the present mount is designed and which is outlined in the drawing is a 37 m/m gun in which the recoiling members move within the receiver 80 which constitutes the cradle. The type of gun will also indicate the feasibility or convenience of mounting the levers singly or in pairs.

85 We claim:

90 1. A mount for guns including a rotatable top carriage formed with a horizontally extended arm, and with uprights between which the gun is to be placed, a rearwardly inclined screw mounted on the extremity of the arm, a nut on said screw, a front lever pivoted to said nut and to the gun in rear of its center of gravity, a rear lever depending from the up-right and pivoted to the gun in position to move on a descending arc 95 on initial elevation of the gun from the horizontal, a bell crank lever connected to the front lever intermediate its ends and forwardly of the center of gravity of the gun and also connected to the up-right at a point 100 which at zero elevation lies in a perpendicular plane including the point of attachment of the rear lever to the up-right and a horizontally disposed equilibrating device associated with said bell crank lever.

105 110 2. A mount for guns including a rotatable top carriage formed with a horizontally extended arm and uprights between which the gun is to be placed, a rearwardly inclined screw mounted on the extremity of the arm, a nut on said screw, a front lever pivoted to said nut and to the gun in rear of its center of gravity, a rear lever depending from the up-right and pivoted to the gun in position to move on a descending arc on initial elevation of the gun from the horizontal, a bell crank lever connected to the front lever intermediate its ends and forwardly of the center of gravity of the gun and also connected to the up-right and an equilibrating device associated with said bell crank lever.

115 120 125 3. A mount for guns including a rotatable top carriage formed with a horizontally extended arm and uprights between which the gun is to be placed, a rearwardly inclined

5 screw mounted on the extremity of the arm, a nut on said screw, a front lever pivoted to said nut and to the gun, a rear lever depending from the upright and pivoted to the gun in position to move on a descending arc on initial elevation of the gun from the horizontal, a bell crank lever connected to the front lever intermediate its ends and also connected to the upright and an equilibrating device associated with said bell crank lever.

10 4. A mount for guns including a top carriage, a pair of gun supporting levers connecting the carriage and the gun in rear of its center of gravity, the rear lever depending from the carriage and positioned on the gun to move on a descending arc on initial elevation of the gun from the horizontal, means for displacing the front lever along 15 an inclined path, a bell crank lever connected to the carriage and to the front lever intermediate its ends and forwardly of the center of gravity of the gun and an equilibrating device associated with said bell crank lever.

20 5. A mount for guns including a top carriage, a pair of gun supporting levers connecting the carriage and the gun, the rear lever depending from the carriage and positioned on the gun to move on a descending arc on initial elevation of the gun from the horizontal, means for displacing the front lever along an inclined path, a bell crank lever connected to the carriage and to the front lever intermediate its ends and an equilibrating device associated with said bell 25 crank lever.

30 6. A mount for guns including a top carriage, a pair of gun supporting levers connecting the carriage and the gun, the rear lever positioned on the gun to move on a descending arc on initial elevation of the gun from the horizontal, means for displacing the front lever along an inclined path, a bell crank lever connected to the carriage and to the front lever intermediate its ends and an equilibrating device associated with said bell 35 crank lever.

40 7. A mount for guns including a support, a lever connecting the support to the rear portion of the gun, a lever connecting the support to the forward portion of the gun, means for displacing the front lever along an inclined path, a bell crank lever connecting the front lever and the support and an equilibrating device associated with the bell crank lever.

45 8. A mount for guns including a support, a lever connecting the support to the rear portion of the gun, a lever connecting

the support to the forward portion of the gun, means for moving the front lever to cause elevation of the gun, a bell crank lever connecting the front lever and the support and an equilibrating device associated with the bell crank lever.

50 9. A mount for guns including a support, a system of levers connecting the gun to the support, the front lever positioned for elevation of the forward portion of the gun, means for bodily displacing the front lever and the rear lever positioned to lower and forwardly displace the rear portion of the gun upon initial actuation of the front lever moving the gun from the horizontal.

55 10. A mount for guns including a support, a system of levers connecting the gun to the support, a front lever positioned for elevation of the forward portion of the gun, means for bodily displacing the front lever and a rear lever positioned to lower the rear portion of the gun upon initial actuation of the front lever moving the gun from the horizontal.

60 11. A mount for guns including a support, a system of levers connecting the gun to the support and means for bodily displacing the foremost lever along an inclined path.

65 12. A mount for guns including a support, and a system of levers connecting the gun to the support, the rearmost lever depending from the support and positioned on the gun to move on a descending arc on initial elevation of the gun from the horizontal.

70 13. A mount for guns including a support, and a system of levers connecting the gun to the support, the rearmost lever depending from the support.

75 14. A mount for guns including a support, a system of levers for connecting the gun to the support, one of the levers being bodily displaceable and an equilibrating device associated with the bodily displaceable levers.

80 15. An elevating mechanism for guns comprising a system of levers arranged to provide a shifting axis of rotation and an equilibrator associated with the foremost of the levers forwardly of the center of gravity of the gun.

85 16. The combination with a gun of means for elevating the gun and gun supporting means positioned with respect to the gun whereby during initial elevation from the horizontal the breech end of the gun is lowered and during subsequent elevation the breech end is raised.
